UNITED STATES PATENT OFFICE.

HARRY C. GOODRICH, OF CHICAGO, ILLINOIS.

RUFFLER AND GATHERER FOR SEWING-MACHINES.

SPECIFICATION forming part of Letters Patent No. 397,908, dated February 19, 1889.

Application filed January 24, 1887. Serial No. 225,272. (Model.)

To all whom it may concern:

Be it known that I, HARRY C. GOODRICH, residing at Chicago, in the county of Cook and State of Illinois, and a citizen of the United States, have invented a new and useful Improvement in Rufflers for Sewing-Machines, of which the following is a full description, reference being had to the accompanying drawings, in which—

- 10 Figure 1 is a side elevation showing the parts in position and the ruffler-blade receded; Fig. 2, a side elevation showing the ruffler-blade advanced; Fig. 3, a reverse side elevation from Fig. 2, with the ruffler-blade advanced; Fig. 4, a section on line $x-x$ of Figs. 2 and 3; Fig. 5, a top or plan view; Figs. 6 and 7, perspective views of the compensating-block; Fig. 8, a cross-section through the presser-foot and compensating-block; Fig. 9, 20 a sectional elevation of the presser-foot, standard, and socket; Fig. 10, a top or plan view of the guard-plate and its support; Fig. 11, a top or plan view of the ruffler-blade; Fig. 12, a detail of the swinging arm or plate and the ruffling-blade; Fig. 13, a perspective view of the ruffle-strip holder; Fig. 14, a detail of the gear for oscillating the ruffler-blade arm or plate; Fig. 15, a detail of the arm or 30 plate for adjusting the throw of the blade; Fig. 16, a cross-section of the arm shown in Fig. 15 on the line 3-3 of said figure; Fig. 17, a detail of the actuating-lever; Fig. 18, a detail of the plate connecting the actuating-lever with the adjusting arm or plate which carries the ruffling-blade; Fig. 19, a plan of an anti-friction plate hereinafter mentioned; Fig. 20, a detail in section of a plate secured to the under side of the presser-foot, showing the bearing-point for the compensating-block; 40 Fig. 21, a detail, being a cross-section through the guide for the upper tape, showing the apex for turning the ruffler-blade transversely.

The objects of this invention are to improve the construction and operation of the 45 compensating-block located on the under side of the presser-foot, and by which inequalities in the level of the feed are overcome, so as to have a uniform pressure upon the material being ruffled, and by which the slipping or 50 drawing back of the material will be overcome; to improve the construction and operation of the ruffling-blade and the devices by

which such blade is given its reciprocating movement; to improve the construction and operation of the devices by which the throw 55 of the oscillating arm or plate which carries the ruffling-blade is adjusted to give the blade the proper amount of throw; and to improve generally the construction and operation of the ruffling attachment as a whole; and its 60 nature consists in the several parts and combinations of parts hereinafter described, and pointed out in the claims as new.

In the drawings, A represents the presser-foot proper, having at its front end a standard, A', for the attachment of the oscillating arm for the ruffling-blade and the actuating lever and devices, and having at its heel end an extension, A'', with a ring portion, a'', which receives the socket A³, by which the 70 ruffler is connected with the presser-foot bar, and, as shown, the socket A³ is attached to the ring a'' by an end or projecting portion, a³, and the attachment of the socket to the presser-foot bar is made by means of a thumb 75 or set screw, a⁴. The presser-foot A, as shown, is in the form of a plate, and is provided with a hole, a, as usual, for the passage of the needle, and, as shown, the standard A' has on one edge a projecting portion or ear, a'.

B is a plate brazed or otherwise firmly secured to the under side of the presser-foot, and having an extension, B', with a portion, B'', which is turned so as to leave between the extension and portion B'' an opening, b'', 85 which forms a guide for the upper binding strip or tape. The plate B is provided with a hole, which, when the plate is in position, forms a continuation of the needle-hole a, and the front edge of the plate on each side of 90 the extension is provided with a turned-down lip, b', and the under side of the plate has formed thereon a projection or point, b, which forms a bearing for the compensating-block.

C is the compensating-block located on the 95 under side of the plate B, and having its contact-face provided with an apex, c, formed by cutting away on each side, so as to leave inclined portions c', as shown in Fig. 7, and the bearing-face of this block is formed to have 100 an inclined face, c'', at each rear corner, and a central apex, c³, so as to leave a face having three bearing-points, as shown in Fig. 6, so that in connection with the apex c and in-

clines c' the block C is free to rock and conform to any inequalities of the feed. As shown, the bearing-edge of the block is straight and rounded off and slightly depressed, so as to leave a free space just back of the bearing-edge for the crimp or ruffle which has been sewed to enter; but this face back of the bearing-edge can be left plain, if so desired.

D is a screw, the stem of which passes through the compensating-block, the plate B, and into the presser-foot A, and the head d' of which enters a depression, d'' , in the compensating-block, which depression is of a larger diameter than the head of the screw, to allow the block to rock and adjust itself to inequalities. The front edge of the block is provided with a recess, d''' , which, when the block is in position, is in line with the needle-hole a for the passage of the needle, and when the block is in position it rests against the point b , so as to have a bearing to give the block a perfectly free movement.

E is a plate bent on itself to form an upper portion, e , and a lower portion, e' , and the upper portion is provided with a notch or recess, e'' , to receive the stem of a set-screw, e^3 , by which the plate as a whole is attached to the presser-foot A, so as to leave a clear space between the two parts e e' for the passage of the strip to be ruffled.

F is the guard-blade, secured at its front end to the arm e' of the plate E, and having at its rear end a slot, f , to line with the needle-hole in the presser-foot, and, as shown, the arm e' in front of the attached end of the blade F is provided with a slot, f' .

G is a ruffling-blade, the actuating end of which is provided with a slot, g , for the passage of the needle, and with teeth g' , as usual, and this blade, when the parts are together, rides above the blade F.

H is a socket, to which the ruffling-blade is secured, and, as shown, this socket has a central cut-away portion, h , leaving strips h' on each end, and a sufficient space or opening to allow the socket to be slipped onto its connecting-stud, and after being slipped into position have the strips h' turned down to lock the socket onto its stud somewhat loosely.

I is a guide-plate having a slot, i , and formed with or connected to a socket, I', which can be slipped over the socket H and attach the guide-plate to the ruffler.

J is an arm, at the free end of which is a stud, j , which receives the socket H, as shown in Fig. 12, the socket being attached by passing the stud through the slot or opening in the socket, as shown in Fig. 12, and then turning the points h' down, as shown in Fig. 1, and to keep the socket from slipping off the stud the outer end of the stud is formed with a head, against which the end of the socket will abut when on the stud. The arm or plate J has an opening, J' , the edge of which has formed thereon two leaves or teeth, j' , as shown in Fig. 12, and this arm or plate J has an ear or side extension, J'' , in which

is a hole, j''' , by means of which the arm is pivoted or suspended on the standard A'.

K is a plate having a hub, k , which is encircled by a ring or band, K', having on its periphery leaves k' , which, when the parts are together, mesh with the leaves j' . This plate K is of a circular form with an ear or extension having projecting arms or pieces k'' k^3 , as shown in Fig. 14.

L is a plate having an elongated slot, l , with a recess or opening, l' , on one side, and one edge of this plate L is provided with ears or projections l'' and l^3 , which, when the parts are together, are in position to come in contact, respectively, with the arms k'' and k^3 of the plate K.

M is the actuating-lever, having at its outer end a fork, M', for the shank of the needle-bar screw, by which the lever is connected with the needle-bar, so that the movement of the needle-bar will operate the lever. The plate L is connected to the lever M by a suitable pin or pivot, m , and when the parts are together the slot l comes in line with the hole which receives the pin or pivot by which the lever is attached to the standard A', so that the slot l will allow of adjustment in the operation of the devices.

N is an extension of the lever M, having on its face a series of ratchet teeth or notches, n .

O is a plate having at its free end a turned portion, o , to lie over the extension N when the parts are together, and having on its main part a projection, o' , which enters the recess l' and connects the plate L with the plate O, so that the movement of the plate O will move the plate L and change the relation of the projections l'' l^3 with reference to the arms k'' k^3 , to produce a variation in the throw of the ruffling-blade, by which such blade will act to produce coarse or fine crimps, as desired.

P is the pin or pivot for attaching the actuating-lever M, provided with plate L, plate K, and arm O to the standard A', the pin passing through a hole in the arm O and the hole in the hub or center k and a hole in the lever M, and forming a pivot for all of these parts, and this pin enters a hole, p' , in the ear a' of the standard A', and is secured in place by riveting or setting down its end.

Q is a pin or pivot connecting the arm or plate J with the standard A', the pin passing through a hole, q' , in the standard A' and entering the hole j'' in the arm J, where it is held by riveting or setting down its end, and, as shown, a washer, p , is placed between the head of the pin P and the face of the arm O, and a washer, q , is placed between the head of the pin Q and the face of the standard A', which washers p q form anti-friction surfaces in the operation of the devices.

R is an anti-friction plate interposed between the face of the standard A' and the faces of the plates J K, and through which anti-friction plate the pins or pivots P Q pass.

The parts are assembled by attaching the compensating-block C in position through the

screw D. The washer R is placed against the face of the standard A', and the arm J is attached to the standard A' by the pin or pivot Q, which is passed through the washer q, standard A', plate R, and arm J. The plate K, with the ring K' and its leaves k', is slipped into the opening J' to have the leaves k' mesh with the leaves j'. The plate L is attached to the lever M by its pivot m, and the plate O is placed against the face of the plate L, with its point o' in the recess l', and the pin or pivot is passed through the hole therefor in the plate O and the slot l in the plate L and the hole in the lever M, through the hole in the hub or center k of the plate K, and entered into the hole p', to be there secured, connecting the several parts together and to the standard A'. The ruffler-blade is connected to the arm J by slipping the socket H onto the stud j and turning down the strips h', which loosely mounts the ruffler-blade upon the stud, and at the same time holds the blade against side play or movement. The arm of the plate E is placed on the ruffler-blade, and there locked by means of the set-screw e³ and slot e'', which secures the blade F in position to lie beneath the ruffler-blade, and when the parts are thus assembled the ruffler is ready for use.

In use the socket A³ is locked to the presser-foot bar by the set-screw a⁴, and the fork M' is connected with the set-screw or other pin on the needle-bar, and when so attached the hole a is in line with the descent of the needle, so that the needle can pass through such hole and the recess d'' in the compensating-block C, and the front edge of the compensating-block is in position to press upon the crimp and hold the material against slipping in either direction. The material on which the ruffle is to be sewed is placed beneath the plate F, so as to be engaged by the feed of the machine, as usual, and the strip or piece to be ruffled is passed through the slot i or the space i' in the guide I, according as it is a right or left hand ruffle, thence over the blade F and beneath the ruffler-blade, and the strip or band for the under side of the ruffled strip is passed through the slot f' and beneath the blade F, and the upper band or strip is passed through the guide-slot b'' above the ruffler-blade, and the several pieces thus brought together are passed beneath the compensating-block and presser-foot, so that the material on which a ruffle is to be sewed is engaged by the feed of the machine to carry forward the several pieces. The movement of the needle-bar reciprocates the lever M, and the movements of this lever oscillate the plate L, bringing the projections l'' l' of such plate in contact with the arms k'' and k³, which oscillates the plate K, and causes the leaves k' through the leaves j' to oscillate the arm or plate J to reciprocate the ruffler-blade. The downward movement of the lever M swings the arm or plate J in a direction to withdraw the ruffler-blade, and

the upward movement of the lever swings the plate J to advance the ruffler-blade, and these movements occur so that as the ruffler-blade is being withdrawn the feed of the machine is acting to advance the material, and as the ruffler-blade is advanced the feed of the machine is non-acting.

The amount of throw given to the ruffler-blade is regulated by the adjusting-arm O in connection with the notches n of the extension N, with which notches the point o'' of the arm O can be made to engage, so as to change the point in the ascent and descent of the actuating-lever at which the projections or ears l'' and l³ engage the arms k'' and k³, thus changing the throw of the arm or plate J. The engagement of the ears l'' l³ with the arms k'' k³ swings the plate J back and forth, the plate being turned to advance the ruffler-blade by the engagement of the ear l'' with the arm k'', and the engagement of the ear l³ with the arm k³ turns the plate J to recede the ruffler-blade, and by making these engagements at various points in the movement of the lever the advance of the ruffler-blade can be increased and its receding movement decreased, or vice versa, to produce coarse or fine crimps.

The outer face of the plate B'' can have an apex formed at a point in line with the center of descent of the needle to act as a bearing-point for the ruffler-blade, by which said blade will be turned slightly transversely to adapt itself to the plane of the compensating-block, and this construction enables the blade to readily adjust itself to any irregularity in the set of the arm J and stud j, or of the socket H in relation to the plane of the presser-foot or compensating-block.

What I claim as new, and desire to secure by Letters Patent, is—

1. The combination, with the presser-foot and ruffler-blade, of the plate B, located on the under side of the presser-foot and having on its under side a projection, b, and the compensating-block C, connected with said plate B, and having an apex, c, and inclines c', said apex being in contact with the projection b of plate B, whereby said block can rock transversely, substantially as described.

2. The combination, with the presser-foot and ruffler-blade, of the plate B, having projection b, and the compensating-block C, provided with an apex, c, and inclines c' c' on its upper face, and having its lower face provided with inclines c'' c'', bearing-point c³, and a front bearing-edge, substantially as and for the purpose specified.

3. The combination, with a reciprocating ruffler-blade and the presser-foot, of the compensating-block C, having apex c, inclines c' c', inclined faces c'' c'', and apex c³, and a connecting-screw, D, for attaching the compensating-block to the presser-foot to rock in all directions, substantially as and for the purpose specified.

4. The combination of a reciprocating ruf-

fling-blade, a presser-foot, the plate B, having a bearing-point, *b*, and ears *b''*, the compensating-block C, having apex *c*, inclines *c' c'*, inclined faces *c'' c''*, and apex *c³*, and the pivot D, substantially as and for the purpose specified.

5. The combination of a reciprocating ruffling-blade, a presser-foot, a plate, B, having an extension, B', provided with a turned portion, B'', to form a guide for the upper band, the compensating-block C, and the pivot D, substantially as and for the purpose specified.

6. The combination of the presser-foot, the swinging arm J, having an opening, J', provided with leaves *j'*, the ruffling-blade G, the plate K, the ring K', having leaves *k'* and arms *k'' k³*, the plate L, having ears *l'' l'*, and

the actuating-lever M, substantially as and for the purpose specified.

7. The combination of the presser-foot, the ruffling-blade, the swinging arm J, having an opening, J', provided with leaves *j'*, the plate K, having a ring, K', provided with leaves *k'* and arms *k'' k³*, the plate L, having slot *l*, recess *l'*, and ears *l'' l'*, the lever M, having notched extension N, and the plate O, having point *o'* and catch *o''*, for changing the position of the plate L to regulate the throw of the ruffling-blade, substantially as described.

HARRY C. GOODRICH.
